RECIPROCATING WORK CARRIER FOR
MARKING MACHINESHerbert P. Hintz, Moline, Ill., and William L.
Klepac, Davenport, Iowa

Application December 29, 1944, Serial No. 570,426

1 Claim. (Cl. 101—4)

(Granted under the act of March 3, 1883, as
amended April 30, 1928; 370 O. G. 757)

1

The invention described herein may be manufactured and used by or for the Government for governmental purposes without the payment to us of any royalty thereon.

The present invention relates generally to the art of impressing or imprinting indicia such as markings, letters, numerals or other symbols onto various articles of metal or other material wherein the application of force is employed through a die or other marking member to produce an identifiable deformation of a permanent character in the article to be marked. This operation is usually termed "symboling" by those skilled in the art and is so referred to hereinafter.

More particularly our invention relates to improvements in presses for performing symboling operations and provides for the symboling of screws, bolts and like material by means of a symboling device operatively connected to a press platen, together with a mechanism for conveying the symbolized articles to a predetermined position under said platen, and means for ejecting them into a suitable receptacle after they have been symbolized. More specifically these results are obtained by means of a holder in which is inserted the symboling die that it is desired to imprint, mounted on the press platen, a ratchet device or indexing mechanism for progressively rotating the mechanism carrying the symbolized articles, and cam means for discharging said articles from said carrying mechanism.

In the past it has been the custom to symbolize screws, bolts and similar articles by placing them in a plurality of spaced holes formed in a heavy rigid metal plate, the size of said holes depending upon the diameter of the articles to be inserted therein. The desired symbol was imprinted by means of an individual hand operation employing a conventional hammer and a hand-held die member. Performance of the work in this manner resulted in physical strain to the worker, which tended to reduce his output, the average person usually being unable to work continuously for more than approximately two hours. The degree to which production was curtailed, of course, depended upon the physical endurance of the individual operator and, in the case of women, it was more noticeable than in men.

Accordingly, one of the objects of the present invention is the provision of a symboling device which can be conveniently operated by women and others of limited physical powers with a minimum of effort.

Another object of the invention is the production of an improved symboling machine that will

be safe to operate, experience with past devices having demonstrated that physical injuries have been inflicted by misdirected blows of hammers used in the symboling operation as carried out in accordance with the teachings of the prior art.

It is another important object of the present invention to provide an improved mechanism for the simple, convenient, speedy and safe symboling of screws, bolts and the like.

10 Another object of the present invention resides in the provision of a structure for automatic ejection of the symbolized articles from the mechanism carrying them.

A still further object of the present invention 15 resides in the provision of an adjustable mechanism enabling various sizes, shapes, and quantities of articles to be symbolized in the same device.

A preferred embodiment of our invention 20 whereby we attain the above and other and further objects is illustrated in the accompanying drawings wherein like numerals refer to like parts throughout the several views, and wherein:

Fig. 1 is an overall front elevation view of a 25 complete press mechanism including an improved symboling device according to our invention;

Fig. 2 is a front perspective view showing one form of work piece carrier used in the symboling operation;

30 Fig. 3 is a plan view showing the indexing and discharge mechanisms of a preferred embodiment of our invention; and

Fig. 4 is a sectional view taken on the line 4—4 of Fig. 3.

35 Referring now particularly to Fig. 1, in which the press mechanism generally is designated 46, there is illustrated a fixed press platen comprising a transverse frame member 1, adapted to receive a slide bar 2 and supported by two uprights

40 3 and 4 secured to the frame of the press. A base 5, adapted to receive the carrying means for articles to be symbolized rests on a table 6. Any convenient method such as hold-down bolts 7 may be employed to secure the base 5 to the table

45 6. A holder 22, in which may be inserted the various die symbols 21, which it is desired to impress or imprint on the articles to be processed, is secured to the slide bar 2. The slide bar 2 is adapted to be moved longitudinally of the frame

50 1 by means of a lever 8 pivotally mounted on the slide bar 2 as at 41 and engaging the fixed frame structure of the press as by means of a slot and pin connection 40. The purpose of the slide bar 2 is to provide means for adjusting the holder 55 laterally within the frame member 1 although in

the actual operation of the device this adjustment is made initially as a setting up operation and the selected position is retained throughout the symboling operation for example by means of a setscrew 44. When it is desired to change the symbol or symbols in the holder 22, this may be accomplished by means of an adjusting member such as the screw shown at 37 in Fig. 1.

A work carrying means such as a notched plate 9, particularly shown in Figs. 2 and 3 and adapted to hold articles to be symbolized, is rotatably mounted on a supporting member 35 positioned on the base 5. The plate 9 is rotatably mounted on a boss 38 forming a pintle and extending from the top of the supporting member 35, the bottom of said plate 9 bearing on the supporting member 35. The plate 9 is held down by means of an ejector cam 23 mounted on the boss 38 as at 24 and hereinafter referred to.

The table 6 which carries the base 5 and the means for holding articles to be symbolized, is raised by the press mechanism by the introduction into said press of fluid pressure such as compressed air through a pedal valve 18 adapted to be depressed by the foot of the press operator. The base 5 is elevated to a point which brings at least one of the articles to be symbolized into forcible contact with the die in the holder 22 as a result of which said article is pressed heavily against said die. As the base 5 is elevated it cooperates with guides 19 and 20 which are machined into the fixed press structure. It will be readily understood that any suitable power system may be employed as a press actuating means, the one chosen to be shown in the preferred embodiment of our invention illustrated and described herein being pneumatic.

Indexing of the notched plate 9 whereby it is progressively rotated is obtained by means of a pawl 10, a link 12 and cooperating mechanism comprising a bell crank lever 13 pivotally mounted on a back member 29 as by means of a pin 32. When the table 6 is raised by depressing the pedal valve 18 the bell crank lever 13 rotates in a counterclockwise direction about its pivot at 32, through the actuation of a drive rod 14. The drive rod 14 is pivotally mounted at its other end on a holding member 15 which in turn is secured to the frame 1. The opposite or operating end 33 of the bell crank lever 13 is connected by a slot and pin connection 34 to the link 12 to the other end of which the pawl 10 is pivotally connected by a pin 41. When the table is raised and the lever 13 is rocked as aforesaid, the link 12 and the pawl 10 are retracted from right to left, as shown in dotted lines in Fig. 2, which action cams the pawl 10 back into the immediately preceding notch in the plate 9, the pawl 10 being forced into the notch by the action of the spring wire 16 mounted on the pawl 10 and the link 12 and held by retainers 47. As the pawl 10 moves out of the notch in the plate 9 in which it is disposed, it exerts pressure on the spring wire 16 and the spring action of said wire forces the pawl 10 into the immediately preceding notch in the plate 9 to which said pawl has been retracted. During this cam retracting operation a stop 30, secured to an extension 39 on the back member 29, as shown in Fig. 3, prevents reverse rotation of the plate 9, and may also serve to limit the forward movement of the pawl 10. The table 6 is lowered by gravity when the foot of the operator is removed from the pedal valve 18 thus causing the link 12 and the pawl 10 to move forward to their initial position. This return movement is effected by the

action of the bell crank lever 13 which rotates about its pivot 32, the left-hand end of the bell crank lever 13 being supported in a raised position by the drive rod 14 and the holding member 15 secured to the frame 1. The forward movement of the pawl 10 brings its straight edge into engagement with the oppositely disposed face of the notch in which said pawl is positioned, which action rotates the notched plate 9 one notch in a clockwise direction. It will be evident, however, to those skilled in the art that by appropriate modifications of the structure herein disclosed, the notched plate 9 could be made to rotate counterclockwise and we do not, therefore, desire to be limited to clockwise rotation. The link 12 rides in a keyway 42 on a bed on top of the vertically raised back member 29 secured to the base 5 and is guided in its movement by a guide plate 36 affixed to said back member 29. A key 45 serves to prevent lateral movement of the link 12.

In the construction of the notched plate 9, best shown in Figs. 2 and 3, it is apparent that the notches are of sufficient depth to accommodate 25 relatively large screws, bolts and the like which are to be symbolized and as shown in Fig. 3 these articles ride well within said notches. The capacity of these notches is sufficient to permit engagement of the pawl 10 with each of the notches in the plate 9 coincidentally with the occupation 30 of said notches by articles to be symbolized, the pawl 10 engaging each of the notches under the head of the screws, bolts or other similar articles to be processed.

As the notched plate 9 advances in its rotational movement, the symbolized articles are discharged therefrom after symboling by means of the ejector cam 23 which is mounted as by means of a screw 24 on the boss 38 on the supporting member 35. A dowel pin 25 also is mounted upon the boss 38 and engages an aperture in the cam 23 to prevent the latter from moving as the plate 9 is rotated. The symbolized articles are discharged from the plate 9 at 26 by being pushed off or guided from said plate by a side edge of the ejector cam 23. The effect of this action is to force them into an appropriately located chute 27 by which they are guided to any suitable receptacle, as at 28, resting on a support, such as 50 47. Premature discharge from the plate 9 is avoided by guards 31 and 43.

Screws, bolts and like material of different shapes, dimensions, lengths, quantities and sizes may be symbolized by the substitution for the plate 55 9 of other similar plates of varying sizes, dimensions and capacities and by adjustment of the drive rod 14. This adjustment is effected by means of a series of adjusting holes such as are illustrated in the bell crank lever 13 and in the holding member 15. The drive rod 14 is adapted 60 to be connected in any suitable way to the holding member 15 and to the bell crank lever 13 by means of the holes shown in each member, the particular holes to be selected depending upon the relationship between the length of stroke of the press during the symboling operation and the size of the article or amount of indexing movement required.

The present invention is especially adapted for 70 use in machine shops for the symboling of various articles such as those described herein and has been found to be highly efficient in increasing production and in providing ease and safety of operation. Many adaptations and modifications of the structure herein disclosed will read-

ily suggest themselves to those skilled in the art without departing from the spirit and scope of our invention. For example, in the preferred embodiment of our invention shown and described herein, the screws, bolts or other articles to be symbolized are manually fed by the operator into the notches in the plate 9. It is evident, however, that suitable mechanism could be employed for accomplishing the feeding automatically and consequently it is not our intention to be limited by the method of feeding herein disclosed.

Accordingly it is our desire to be limited herein only by the prior art and the appended claim.

We claim:

15 A symboling machine comprising a fixed upright base having an upward, overhanging portion including a stamping die, a carrier portion mounted on the base below the die and arranged for vertical motion to and from the die, a disc member having peripheral notches mounted on the carrier portion for rotation about a vertical axis, means on the carrier providing a guideway extending generally tangentially to the disc member, a slider in the guideway carrying a spring-biased pawl engageable with the said notches for step-by-step rotation of the disc member, a bell-crank medially pivoted on the said means, and with one distal end engaging the slider and the other articulated to the said overhanging portion of the base whereby the pawl is reciprocated horizontally on cyclic vertical motion of the carrier portion, a guide member positioned to urge

5 work pieces into snug engagement with the notches in the region of the die, resilient means extending within the outer periphery of the disc, yieldable to pawl-urged motion of the disc but rigidly retaining the disc against reverse motion, and a cam positioned on the carrier centrally of the disc and extending to the peripheral region of the notches for removal of the work pieces.
